UNITED STATES PATENT OFFICE.

WILLIAM H. McCULLOUGH, OF CHICAGO, ILLINOIS, ASSIGNOR TO J. W. MOOREHEAD,
TRADING AS RAYBURN HUNTER & COMPANY, OF CHICAGO, ILLINOIS.

LIGHTNING-ROD-CONNECTING CLAMP.

1,181,399.

Specification of Letters Patent. Patented May 2, 1916.

Application filed March 1, 1915. Serial No. 11,153.

To all whom it may concern:

Be it known that I, WILLIAM H. McCULLOUGH, a citizen of the United States, and a resident of the city of Chicago, in the county of Cook and State of Illinois, have invented 5 certain new and useful Improvements in Lightning-Rod-Connecting Clamps, of which the following is a specification.

My present invention relates to improvements in lightning conductors, and more specifically to a form of joint or clamp employed in the assembling of any of the well-known forms of lightning rods, or in the securing of such a rod to its support; in the 15 first instance, securing the maximum of efficiency consistent with the material of which the rod is made, and in the second instance, forming an easily installed and effective clamp for securing the rod to its support.

20 I accomplished the above objects by means of the clamp illustrated in the accompanying drawing, in which:—

Figure 1 is an elevation of a piece of rod with the usual form of coupling pressed 25 upon each end thereof, and with my clamp shown in place intermediate the couplings; and Fig. 2 is a central horizontal section through my assembled clamp as shown in Fig. 1, the rod having been omitted for the 30 purpose of clearly disclosing the arrangement of the divers elements going to make up my clamp.

Similar reference characters refer respectively to similar parts throughout the two 35 views.

The rod proper to which my device is more adapted to be applied, consists preferably, as I have shown, of four longitudinally disposed, spirally inclined webs, 3, being 40 respectively star shaped in cross section, the webs radiating from a common center.

My improved clamp consists primarily of two substantially symmetrical sections 4 and 5, adapted to surround the rod, 3, and to be 45 drawn together by suitable means, such as screws, 6, one being located on each side of said clamp, as clearly shown. The walls of the clamp (Fig. 2) are each respectively provided with a wedge shaped projection, 50 4^a—5^a, lying diametrically opposite one another, and being cast integral with their respective sections, each being adapted to enter between two of the webs of the rod, 3, and to substantially conform to their peripheral contour.

It will now be seen that by clamping the two sections 4 and 5 together about a form of rod as described, with the radiating webs, 3, as shown, the wedges 4^a and 5^a will enter intermediate the flanges, 3, and being wedged in will contact their surfaces, thus adhering and becoming firmly secured thereto. However, to facilitate the locking power of my clamp and in order to assemble the divers sections of rod together securing the maximum of efficiency consistent with the material of which the rod and coupling are made, I introduce two wedge shaped members, 7 and 8, substantially of the same shape as the before mentioned projections 4^a and 5^a only being separate and apart from the clamp proper, and adapted to enter the two diametrically opposite openings formed by the webs of the rod, 3, and lying adjacent those already filled by the 75 projections 4^a and 5^a.

Protruding at right angles to the plane of the rod and being cast integral with one section of my clamp, (preferably 5 as shown) is a threaded stud, 9, which is 80 adapted to receive the usual form of tapped coupling A, as I have shown, swaged to the upper end of rod, 3, in Fig. 1. It is also capable of receiving any conventional form of socket, which in turn is secured to the 85 support to which the rod itself is adapted to be secured.

It will be obvious from the foregoing description and drawing, that in assembling the rod, or in securing the rod to its support, the section 5, will be secured first, either to a coupling A, or to a bracket that has already been attached to the rod's support, then the rod is inserted into that half of the clamp so that the projection 5^a may 95 register between two of the flanges, 3; the two wedges 7 and 8 are then inserted as shown, and the remaining half, 4, of my device is assembled and clamped to 5.

Having thus described my invention, what 100 I claim as new and desire to secure by Letters Patent is:—

1. A clamp for a lightning-rod comprising two sections adapted to surround said rod and to be secured together, and integral 105 projections provided upon each respective section for engaging said rod.

2. A coupling for a lightning-rod comprising two sections adapted to surround said rod and to be clamped together, means 110

- provided upon each respective section for engaging said rod, and separate means adapted to engage said rod and to be held in place by the above mentioned sections.
- 5 3. A coupling for a lightning-rod comprising two sections adapted to surround said rod and to be clamped together, the inner periphery of said sections adapted to conform to and engage the periphery of said 10 rod, separate means adapted to engage the above said rod, the last said means adapted

to be held in engagement therewith by said sections, and means integral with one of said sections adapted to receive a coöperating member.

15

In testimony whereof I affix my signature in the presence of two witnesses.

WILLIAM H. McCULLOUGH.
